Attys.*

UNITED STATES PATENT OFFICE.

MOSES F. CARR, OF LEXINGTON, MASSACHUSETTS, ASSIGNOR, BY MESNE ASSIGNMENTS, TO THE BASSICK MANUFACTURING COMPANY, OF CHICAGO, ILLINOIS, A CORPORATION OF DELAWARE.

DUST CAP FOR LUBRICANT-RECEIVING NIPPLES.

Application filed November 18, 1924. Serial No. 750,589.

This invention aims to provide an improved dust cap for lubricant-receiving nipples.

In the drawings, which illustrate a preferred embodiment of my invention:

Figure 1 is a side elevation of a lubricant-receiving nipple showing the dust cap secured thereto;

Fig. 2 is a section on the line 2—2 of Fig. 10 1, being partly in elevation;

Fig. 3 is a section on the line 3—3 of Fig. 2, being partly in elevation; and

Fig. 4 is a section corresponding to Fig. 2, but showing the relative position of the 15 parts as the cap is being passed over the nipple.

Referring to the drawings, I have shown a lubricant-receiving nipple presenting an enlarged central portion 1 having relatively 20 steep pitch threads 2 for engagement with a lubricant-expelling device. At one side of the central portion, I have provided a reduced portion 3 threaded for engagement with a part to be lubricated, and at the 25 other side of the central portion 1, I have provided a cylindrical portion 4 for peripheral engagement by a sealing element in the nozzle of a lubricant-expelling device. Between the central portion 1 and the cylindrical portion 4, I have provided a neck 5, as best illustrated in Fig. 2, this neck 5 is preferably closely adjacent the outer end 30 of the threaded portion of the nipple.

The cap, for use with a nipple of the 35 above-mentioned description, is formed from two sheet metal stampings 6 and 7 (Fig. 2), which, when secured together, provide a body portion 6 having a closed end 8 for excluding dust and dirt from the lubricant-receiving end of the nipple, which, 40 preferably as illustrated, is closed by a check valve being shown as a ball protruding somewhat from the end of the nipple. The body portion 6 completely covers the cylindrical 45 portion 4 of the nipple and the open end skirt portion 7 completely covers the threads 2 of the enlarged central portion 3 of the nipple, as shown in Fig. 2. The cap, as illustrated, presents opposite the neck in the nipple an enlarged portion formed by flanges 10 and 11 of the stampings 6 and 7 respectively.

This enlarged portion constitutes a convenient finger grip for use in withdrawing

the cap from the nipple. Where, as in the preferred form of my invention illustrated, 55 the flanges 10 and 11 are spaced apart, preferably by a flange 16, the enlarged portion also provides a housing for a spring which preferably, as illustrated, includes a body portion 12 fitting the interior of the wall 16 between the flanges 10 and 11, and also presenting resilient jaw means, herein shown as an intersecting jaw 13 adapted to engage the neck in the nipple at one side only (Fig. 3). Where the parts are arranged in the 60 relative positions shown, this resilient jaw portion not only holds the cap on the nipple, but because it abuts against the threaded portion of the nipple, prevents the cap from 65 presenting resilient jaw means, herein shown as an intersecting jaw 13 adapted to engage the neck in the nipple at one side only (Fig. 3). Where the parts are arranged in the relative positions shown, this resilient jaw portion not only holds the cap on the nipple, but because it abuts against the threaded portion of the nipple, prevents the cap from being thrust onto the nipple to such an extent that the check valve in the nipple will be opened by the closed end 8 of the cap. 70

The body portion 12 of the spring extends at least half the distance around the interior of the spring casing (Fig. 3) thereby 75 preventing lateral shifting of the body of the spring. The jaw 13 of the spring extends from one end of the body portion 12 into contact with the neck of the stud and then the free end of the jaw 13 extends between the flanges 10 and 11 to prevent transverse shifting of the spring jaw 13 during engagement and disengagement of the cap with the nipple. The one point contact of the jaw 13 is important in that it reduces 80 the friction between the spring jaw means and the cylindrical portion 4 of the nipple as it passes thereover during engagement and disengagement of the cap with the nipple. 85

The skirt portion 7 of the cap being of greater diameter than the cylindrical portion 4 of the nipple, serves an important function during passage of the cap onto the nipple, in that it permits, and even induces 90 inadvertently, such tipping of the cap relative to the nipple, when the outer face of the nipple abuts against or comes opposite the spring jaw 13, as causes the edge of the outer end of the nipple to assume a position 95 where it can wedge the spring jaw out of nipple-intercepting position, as is best shown in Fig. 4. When the head of the nipple, while thus tipped abuts against the shoulder 14, the body portion 6, which is 100 between the fingers during the entering op-

- eration, provides a handle or lever for straightening the cap on the nipple and thereby pressing back the spring a sufficient distance so that the cap can be advanced 5 until the spring jaw 13 engages the neck of the nipple. The foregoing manipulation is automatic in the sense that it requires no advertent sequence of manipulatory movements on the part of the person applying 10 the cap to the nipple, each successive movement following naturally the ordinary and obvious application of pressure by the ends of the fingers to the outer face of the flange 10. Even if the initial entering angle is 15 such that the end of the nipple abuts against the spring a slight pressure will cause the cap to tip to the position shown in Fig. 4. The fact that the interior of the shoulder 20 14 (and incidentally of the entire body portion 6) is of smaller diameter than the interior of the skirt portion 17, is of importance in that this provides a surface (the one opposite the spring jaw 13) which the spring jaw 13 may press against the cylindrical portion of the nipple. The corresponding side of the skirt portion 7 is urged 25 toward the adjacent portion of the nipple and may bear thereagainst if the clearance of the cylindrical portion of the nipple in 30 the cylindrical portion 6 of the cap is not so proportionately small as to cause the inner face of the body portion 6 first to bear against the adjacent portion 15 of the head of the nipple.
- 35 Withdrawal of the cap from the nipple may be effected by a direct pull against the flange portion 12, the spring jaw 13 riding up the sloped shoulder between the neck and the cylindrical portion of the nipple. This 40 withdrawal may be particularly easily effected by a slight turning of the cap on the nipple. During this turning movement, the spring turns with the cap so that the travel of the spring jaw 13 up the sloped shoulder 45 is relatively gradual as compared with its abrupt movement when the cap is withdrawn without turning movement. I have found that the majority of people using the caps instinctively turn the cap somewhat 50 during withdrawal.
- The body portion 12 of the spring exerts 55 resilient pressure against the inner surrounding surface of the casing, so that the spring cannot as a whole shift transversely of the casing when the spring jaw is pressed outwardly, clearance being provided only at the 60 spring jaw to permit maximum outward flexure thereof while the cap is being slipped on or off the nipple. The resilient pressure of the body against the casing also causes the 65 spring to turn with the cap during turning of the latter when the cap is being withdrawn from the nipple.
- In assembly, the flange 16 extending from 70 the flange 11 of the skirt portion 7, fits into 75 the cylindrical flange portion 17 extending from the flange 10 of the body portion 6 and a portion of the flange 17 is crimped or rolled over the flange 11 to secure the skirt 7 and body 6 together, thereby forming the 80 casing for the spring as best illustrated in Fig. 2.
- While I have shown and described a preferred embodiment of my invention, it will be understood that I have done so for purposes of clarification and not for limitation, my invention being best defined in the following claims.
- I claim—
1. A dust cap for a lubricant-receiving nipple comprising, in combination, a body portion, an open end skirt portion, an enlarged portion between said body portion and said skirt portion and a spring contained in said enlarged portion, said spring presenting jaw means for engagement with the nipple at one side only. 85
  2. A dust cap for a lubricant-receiving nipple comprising, in combination, a body portion, an open end skirt portion, an enlarged portion between said body portion and said skirt portion, a spring contained in said enlarged portion, said spring including a body portion extending at least half the distance around and against the inner circumference of the enlarged portion to prevent lateral shifting of the spring, and a resilient jaw extending from one end of said body portion of the spring for engagement with the nipple at one side only. 90
  3. A dust cap for a lubricant-receiving nipple comprising, in combination, a body portion, an open end skirt portion, an enlarged portion between said body portion and said skirt portion, a spring contained in said enlarged portion, said spring including a body portion extending at least half the distance around and against the inner circumference of the enlarged portion to prevent lateral shifting of the spring, and a resilient jaw extending from one end of said body portion of the spring, said jaw having its free end located between the body portion and the skirt portion of the cap to prevent movement of the jaw in a direction parallel with the axis of the cap when engaging and disengaging the nipple. 95
  4. A dust cap for a lubricant-receiving nipple comprising, in combination, a casing, a spring jaw intersecting one side of the nipple-receiving aperture in said casing, said casing providing opposite said spring jaw a clearance sufficient to permit entrance of the head of the nipple past said spring without substantial shifting of said spring jaw, while providing beyond said spring a lesser clearance insuring substantial lateral shifting of said spring by the head of said nipple as said cap passes further onto the nipple, whereby to provide substantial cap- 100

retaining pressure of said spring on the nipple when the two are fully engaged.

5. A dust cap for a lubricant-receiving nipple comprising, in combination, a pressed metal cap containing a spring jaw located at one side of the cap for engagement with the nipple, said cap providing opposite said spring sufficient clearance to permit initial passage of the head of the nipple past said 10 spring when said cap is angled relative to said nipple without substantial flexing of said spring jaw, and beyond said spring an abutment provided by said cap beyond said spring for enforcing straightening movement of said cap relative to said nipple as the cap is advanced further onto the nipple, said spring jaw yielding laterally during such straightening movement of the cap.
6. A dust cap for a lubricant-receiving 20 nipple comprising, in combination, a casing presenting a nipple-receiving aperture, a spring jaw intersecting one side of said aperture, an open end skirt portion at one side of the spring of a diameter sufficient to permit the head of the nipple to be entered past

said spring jaw without shifting thereof when said casing is angled relative to the nipple, and an enlarged finger portion and body portion of said casing for enforcing straightening movement of said casing as it 30 is advanced further onto the nipple for engagement of the spring jaw with the neck on the nipple.

7. A dust cap for engagement with a lubricant receiving nipple having two work 35 engaging portions of different diameters, said cap comprising a hollow casing containing a spring presenting a spring jaw portion intersecting the passage into said casing for resiliently holding said cap on the nipple, said cap having two interior portions of different diameters corresponding to the said diameters of said nipple spaced apart by said spring jaw portion, said interior portions of said cap being resiliently urged by said jaw into bearing engagement with the said portions of said nipple.

In testimony whereof, I have signed my name to this specification.

MOSES F. CARR.
